CHIMNEY LINER EXTENSION

Lester H. Munyon, Spokane, Wash.

Application July 27, 1944, Serial No. 546,789

1 Claim. (Cl. 72—88)

This invention relates to an extension for a chimney liner and it is one object of the invention to provide a device of this character formed of sheet metal and of such construction that it may be applied to a protruding portion of a liner and firmly secured in upright position.

Another object of the invention is to provide an extension having a slip joint extending longitudinally of one wall, the interfitting portions of the metal sheet from which the extension is formed being pivotally connected at the upper end of the joint so that the lower portion of the extension may be expanded or contracted and applied to the protruding end portion of the chimney liner in frictional gripping engagement therewith.

Another object of the invention is to provide a joint formed by folding a side edge portion of the metal sheet from which the extension is formed and of such formation that while the lower portion of the extension may be expanded and contracted, leakage of air through the joint will not be likely.

Another object is to provide the extension with means at its lower end for effecting tight binding grip between the extension and the chimney flue liner to which it is applied.

Another object is to provide the extension with members for resting upon the upper end of a chimney liner and provide a good support for the extension when said extension is fitted within the liner.

In the accompanying drawing:

Fig. 1 is a perspective view showing the improved extension applied to a protruding upper end portion of a chimney liner and tightly clamped about the liner.

Fig. 2 is a sectional view on the line 2—2 of Fig. 1.

Fig. 3 is a perspective view showing an extension mounted within the protruding upper end portion of a chimney liner.

Fig. 4 is a sectional view on the line 4—4 of Fig. 3.

Fig. 5 is a sectional view, on an enlarged scale, taken transversely through the upper end of the slip joint.

This improved extension is intended to be applied to the liner 1 of a chimney and, when it is applied, it has frictional gripping engagement with the portion of the liner which protrudes from the top of the chimney. It may fit about the protruding portion of the liner, as shown in Figs. 1 and 2, or fit within the liner, as shown in Figs. 3 and 4.

The extension is formed from a rectangular sheet of metal of suitable length and width, bent to form a tubular extension 3 having opposed side walls, one of which is indicated by the numeral 4 and is formed intermediate its width with a slip joint 5 extending the full height or length of the extension. This joint is shown on an enlarged scale in Fig. 5, and, referring to this figure, it will be seen that a side edge portion of the metal sheet is folded back and forth upon itself to form a pocket 6 open along its outer side edge and having inner and outer walls 7 and 8. The other side edge portion of the metal sheet fits within the pocket 6 and, at its upper end is secured by a rivet 9 which serves as a pivot pin and permits the interfitting portions of the wall 4 to have swinging adjustment transversely of the wall and its joint. Therefore, when the extension is applied to the liner, the lower end of the extension may be expanded and fitted about the protruding portion of the liner and have snug fitting engagement therewith, or the lower end of the extension may be thrust into the liner and then expanded for close fitting contact with walls of the liner.

When the extension is fitted about the liner, it must be constricted into tight frictional binding engagement with the liner, and to do so there have been provided clamps 10, each of which consists of brackets 11 fixedly secured against the wall 4 with the joint 5 disposed between the brackets. These brackets have ears 12 projecting laterally from the wall 4 and formed with openings to receive a bolt 13 which has its head engaging the outer side face of the ear of one bracket and its nut 14 bearing against the outer side face of the ear of the other bracket. When the nut is tightened the brackets are drawn toward each other and the lower end of the extension will be contracted into tight binding engagement with the liner.

When the extension is to be fitted within the liner instead of about the same, a single set of brackets 15 are secured to the wall 4 at opposite sides of the lower portion of the joint. The flanges 16 are braced by horizontal webs 17 and the bolt 18 passes through openings in the ears, with its head engaging the outer side face of one ear. Two nuts 19 are carried by the bolt 18 and engage confronting side faces of the ears, so that, by turning the nuts, the brackets may be shifted away from each other and the lower end of the extension expanded into tight binding engagement with walls of the liner. Strips of angle metal 20 are secured horizontally against side

walls of the extension in the plane of the brackets 15 and the horizontal flanges of the strips 20, and the brackets serve to contact the upper ends of walls of the liner and limit downward movement of the extension into the liner. Therefore, the extension will be supported when applied to the liner and prevented from slipping downwardly into the liner beyond the position shown in Fig. 3.

In both embodiments of the invention illustrated and described, the extension may be expanded and contracted at its lower end when applied to the liner and held in tight frictional binding engagement with walls of the liner. The fact that the interfitting portions of the wall 4 are pivotally secured at the upper end of the slip joint 5, retains these portions in overlapping engagement with each other and eliminates an open crevice through which air could pass and interfere with efficient drawing of the chimney.

Having thus described the invention, what is claimed is:

An expandible and contractible extension for a chimney flue liner comprising a sheet of metal formed into a tube provided with an expansion joint extending its full height and formed by folding a side edge portion of the sheet metal, back and forth to form a pocket open along its outer side and fitting the other side edge portion of said sheet metal into the pocket, a pin passing through the upper ends of the interfitting portions 10 of the sheet metal and pivotally connecting same, brackets carried by said wall at opposite sides of said joint and having ears projecting laterally from the tube, and a bolt passing through said ears and carrying nuts abutting confronting side 15 faces of the ears to expand the tube for tight fit within a chimney flue liner, and cleats projecting laterally from the tube cooperating with the brackets for resting upon the upper ends of the flue liner and supporting the tube in the liner.
